DESIGN FOR A HOUSE

Robert G. Le Tourneau, Peoria, Ill., assignor to R. G. Le Tourneau, Inc., Stockton, Calif., a corporation of California

Application January 18, 1943, Serial No. 109,283

Term of patent 14 years

To all whom it may concern:

Be it known that I, Robert G. Le Tourneau, a citizen of the United States, residing at Peoria, in the county of Peoria and State of Illinois, have invented a certain new, original, and ornamental Design for a House, of which the following is a specification, reference being had to the accompanying drawing, forming a part thereof.

In the drawing:

Figure 1 is a perspective view of the house, looking at the front side and one end and showing my new design; and

I claim:

The ornamental design for a house, as shown.

ROBERT G. LE TOURNEAU.
